ATTORNEY

UNITED STATES PATENT OFFICE

JAMES V. VANDAGRIFF, OF WEATHERFORD, TEXAS

MATCH RECEPTACLE

Application filed June 23, 1928. Serial No. 287,776.

This invention relates to match boxes or safes primarily adapted for use upon advertising placards and the like.

An object of the invention comprehends 5 a housing for a match box mounted upon the placard.

Another object of the invention contemplates a striking surface upon the housing.

More specifically stated the placard is 10 provided with an opening through which the matches may be withdrawn or delivered.

With the above and other objects in view, the invention further consists of the following novel features and details of construction, to be hereinafter more fully described, illustrated in the accompanying drawing and pointed out in the appended claim.

In the drawing:

Figure 1 is an elevation of my invention. 20 Figure 2 is a sectional view taken on line 2—2 of Figure 1.

Figure 3 is a horizontal sectional view taken through the invention.

Referring to the drawing in detail, where- 25 in like characters of reference denote corresponding parts, the reference character 10 indicates a base or supporting member having a placard 11 carried by and upstanding therefrom in the manner as illustrated in

30 Figure 2 of the drawing.

The placard 11 is adapted for advertising purposes and from the illustration in Figure 1 of the drawing, it is noted that a tobacco advertisement is effectively displayed. The placards may be made any desired size but are preferably miniature in order that the same may be used upon desks and the like. A housing 12 of U-shaped formation, carried upon the upper side of the base or supporting member 10 and behind 40 the placard 11, is adapted to dispose the open side thereof toward the adjacent surface of said placard.

The side edges of the open side of the 45 housing terminate to provide outwardly and laterally disposed flange portions 13 and 14 respectively, which in turn define channel portions 15 and 16. The channel portion 15 is adapted to accommodate one side edge of 50 the placard 11 whereas the channel portion

16 is adapted to engage one side edge of a slotted portion 17 in the placard 11. The outer surface of the channel portion 15 is serrated, as at 18, to provide a surface upon which matches may be struck.

The drawer portion 19 of a match box, not shown, is adapted for reception within the housing 12, in the manner as illustrated in Figure 2 of the drawing. The open side of the drawer is exposed to the inner surface of the placard 11. Furthermore, the placard is provided with semi-circular oppositely disposed cut-out portions 20, having communication upon the opposite sides of an elongated horizontally disposed slot 21. As noted in Figure 1, the registering semi-circular cut-out portions 20 permit insertion of a finger within the drawer portion 19 of the match box, whereby the matches may be discharged or delivered through the 70 slot 21.

It is to be noted that the invention not only advertises smoking tobacco but which also exhibits means for using same.

It is to be understood that the cover design of the placard may be employed for advertising any suitable article of merchandise.

The invention is susceptible of various changes in its form, proportions and minor details of construction, and the right is herein reserved to make such changes as properly fall within the scope of the appended claim.

Having thus described the invention, what 85 is claimed is:—

A match receptacle comprising a base member having a placard, said placard having slotted portions, a housing carried upon the base member behind the placard, flange portions carried by and laterally disposed in opposite directions from the housing, said flange portions being shaped to form channels projected through the slotted portions in the placard, and the placard being further provided with portions removed in communication with the enclosure defined between same and the housing.

In testimony whereof I affix my signature.

JAMES V. VANDAGRIFF.
